UNITED STATES PATENT OFFICE.

JOHN DUNKIN LODGE AND WILLIAM C. PELL, OF BRIDGEPORT, WEST VIRGINIA; FLORA N. PELL, COMMITTEE OF WM. C. PELL, AN INSANE PERSON; SAID LODGE AND SAID COMMITTEE ASSIGNORS TO SAID JOHN DUNKIN LODGE.

MACHINE FOR MAKING CONCRETE BLOCKS.

1,220,521.

Specification of Letters Patent. Patented Mar. 27, 1917.

Application filed May 3, 1916. Serial No. 95,203.

To all whom it may concern:

Be it known that we, JOHN D. LODGE and WILLIAM C. PELL, citizens of the United States, residing at Bridgeport, in the county 5 of Harrison and State of West Virginia, have invented a new and useful Machine for Making Concrete Blocks, of which the following is a specification.

The present invention appertains generally to molding machines, and aims to provide a novel and improved machine for making concrete or other plastic blocks.

It is the object of the invention to provide a machine of the character indicated 15 embodying a mold, a ram for pressing the concrete within the mold, a table or movable bottom for the mold, and a novel actuating mechanism for operating said ram and table, said mechanism being controllable to 20 bring the ram and table into play at the proper time, whereby the ram is first moved into the mold to compress the concrete therein, and is then retracted and moved out of the way, after which the table is raised to 25 raise the completed block out of the mold for the removal of the block, the table then being returned so that another charge of concrete can be dumped into the mold for a new operation.

30 The present machine has improved features of construction and operation, whereby to facilitate the operation, there being means for stopping the ram and table at the proper time, as when the ram is moved 35 into the mold to a predetermined distance and is retracted and moved out of the way, and when the table is raised to eject the block from the mold, and is retracted to normal or initial position. By the provision 40 of such means, the operation of the ram and table is automatically stopped at the proper positions thereof, to relieve the operator of this responsibility, but the machine has means whereby the operator can 45 quickly bring the several parts into operation.

Another object of the invention is the provision in a block molding machine, the combination with the mold and block ejecting means, of novel means for removing the ejected block from above the mold to one side thereof, out of the way of the ram.

50 A still further object of the invention is the provision of means for centering the ram

when it is returned from one side of the 55 mold to a position above the mold to enter the same.

It is also within the scope of the invention to provide a machine having the characteristic features above noted, and which 60 is improved generally in its construction and details, to enhance the efficiency and utility thereof.

With the foregoing and other objects in view which will appear as the description 65 proceeds, the invention resides in the combination and arrangement of parts and in the details of construction hereinafter described and claimed, it being understood that changes in the precise embodiment of 70 the invention herein disclosed can be made within the scope of what is claimed without departing from the spirit of the invention.

The invention is illustrated in the accompanying drawings, wherein:—

75

Figure 1 is an elevation of the machine.

Fig. 2 is another elevation thereof looking at right angles to the line of view in Fig. 1.

Fig. 3 is a sectional detail showing the friction wheels.

80

Fig. 4 is a plan view showing the intermediate friction wheel and its yoke.

85

Fig. 5 is a fragmental detail showing the connection of the ram with its actuating mechanism.

Fig. 6 is a detail view illustrating a part 90 of the controlling means.

Fig. 7 is another detail view of the controlling means.

Fig. 8 is an elevation of the parts shown 95 in Fig. 7 looking at right angles to the line of view in said figure.

Fig. 9 is a fragmental plan view showing the controlling lever.

Fig. 10 is a fragmental elevation of the 95 mold and block removing device showing the block supporting brackets moved toward one another.

Fig. 11 is a sectional view taken on the line 11—11 of Fig. 2, portions being broken 100 away, showing the block supporting brackets swung into position to engage the ejected block.

Fig. 12 is a plan view of the mold and ram centering means.

105

The machine has a frame of suitable construction, and is supported in any suitable manner, said frame comprising a base 1,

standards 2 secured to the base, and a yoke member 3 attached to the upper ends of the standards.

Mounted upon the base 1 is a mold 4 having its top and bottom open, and a table or bottom plate 5 is movable within the mold and is supported by rack bars 6 to the upper ends of which the table is secured. The rack bars 6 slide through the base 1 and mesh with pinions 7 secured upon the shaft 8 journaled to the base. This shaft 8 is rotated, as will hereinafter more fully appear, for raising and lowering the table, the table being raised to lift or eject the completed block from the mold, in order that the block can be readily removed.

The block removing device embodies a rock shaft 9 having its terminals journaled in bearing brackets 10 attached to the mold 4 adjacent its upper edge, and brackets 11 are slideable or feathered upon the rock shaft 9 adjacent the terminals thereof and between the brackets 10. These brackets 11 have outstanding arms 12, and arms 13 arranged at right angles with the arms 12 and offset relative thereto, the arms 12 being closer together than the arms 13. The arms 13 are normally spaced from the mouth of the mold. A hand lever 14 is fulcrumed, as at 14^a, to the rock shaft 9 between its ends, and is connected by links 15 with the brackets 11, whereby said lever 14 can be swung in two directions, to slide the brackets 11 toward and away from one another, and to rock the shaft 9. The operation of this device will be explained hereinafter under the operation of the entire machine.

The ram 14' is suspended from the superstructure and has its upper end journaled upon a crank or wrist pin 15' connecting a pair of gear wheels 16, which are journaled for rotation, as at 17, within the frame member 3, whereby said gear wheels 16 in being rotated in one direction, will depress the ram, and in being rotated in the opposite direction, will raise or retract the ram from the mold.

The actuating mechanism embodies pinions 18 meshing with the gear wheels 16 and secured upon a counter shaft 19 journaled upon the member 3, and gear wheels 20 are also secured upon the shaft 19 and mesh with pinions 21 secured upon another counter shaft 22 journaled upon the member 3. A friction wheel 23 is secured upon the shaft 22 to be engaged by a friction wheel 24 below it. This friction wheel 24 is mounted upon an actuating shaft 25 journaled in bearings 26 carried by a yoke or lever 27 whose terminals engaged a fulcrum rod 28 carried by brackets 29 attached to one end of the member 3. The yoke 27 projects inwardly toward the center of the frame and has an inwardly projecting arm 30, and when said arm 30 is raised, the friction wheel

24 is brought into contact with the friction wheel 23, whereby the shaft 25 in being rotated will transmit motion to the gear wheels 16 at a proper speed ratio, whereby the wheels 16 are operated much slower than the actuating shaft 25 but with greater power, in order that the ram will be operated properly.

Mounted for rotation upon the actuating shaft 25 at the opposite sides of the frame are loose pulley wheels 31 and 32, which are rotated in the opposite directions, by means of belts (not shown) or other suitable means. Coöoperating with the pulley wheels 31 and 32 are the respective clutch boxes 33 and 34, and a bar 35 is terminally connected with the clutches. The clutches are for the purpose of connecting the pulley wheels 31—32 with and disconnecting them from the driving shaft 25. When the bar 35 is in intermediate position, the clutches are open, and the pulley wheels are disconnected from the shaft 25, and when the bar 35 is moved in one direction, one clutch is thrown in for connecting the respective pulley wheel with the shaft, while when the bar 35 is moved in the opposite direction, the other clutch is thrown in for connecting its pulley wheel with the shaft 25. Thus, by shifting the bar 35 in one direction or the other, from intermediate position, it is possible to rotate the shaft 25 in either direction.

As a means for shifting the clutch bar 35, a lever 36 has one end pivotally connected with the bar 35 between its ends, and said lever 36 is fulcrumed, as at 37, to a transverse bar 38 attached to a pair of the standards 2. The lever 36 is provided with a slot 39 receiving the lug 40 projecting from a collar 41 which is secured upon a sliding and rocking shaft 42 mounted for sliding and rotary movements in bearings 43 attached to those standards 2 to which the bar 38 is fastened. When the shaft 42 is slid longitudinally, the lug 40 in working in the slot 39, will swing the lever 36, to reciprocate the bar 35, and as a means for manually shifting the shaft 42, a collar 44 is disposed loosely thereon adjacent one bearing 43, and is provided with an annular groove 45 in which a finger 46 carried by said bearing engages, to prevent the longitudinal movement of the collar 44, but to permit the same to oscillate. The collar 44 has a bracket 47 to which is fulcrumed a controlling lever 48, and said lever has a loop or yoke 49 surrounding the shaft 42, and pivoted thereto, as at 50, whereby when the lever 48 is swung by hand, it moves the shaft longitudinally. When the lever 48 is swung either upwardly or downwardly, it will rotate the shaft 42, which is utilized for controlling the yoke 49 and friction wheel 24 carried thereby. Thus, the collar 41 has an arm 51 projecting therefrom which is con-

nected by a link 52 with the arm 30. Consequently, when the lever 48 is raised, the arm 51 is moved downwardly, to pull the link 52 and yoke 27 downwardly, thereby 5 removing the friction wheel 24 away from the friction wheel 23, and disconnecting the actuating shaft 25 from the ram operating device.

The shaft 8 is also rotated by the actuating shaft 25, for raising or lowering the table, and to this end, a worm wheel 53 is secured to the shaft 8 at one side of the base 1, and meshes with a worm 54 secured to the lower end of a vertical shaft 55 journaled 10 through bearings 55^a carried by the frame. A bevel gear 56 is secured to the upper end of the vertical shaft 55 and meshes with a bevel gear 57 secured to one end of a shaft journaled to the member 3 below the yoke 27. Secured upon this shaft 58 is a friction wheel 59, and the friction wheel 24 is disposed intermediate the friction wheels 23 and 59 to alternately engage them when the yoke 27 is moved upwardly and downwardly. When the yoke 27 is in an intermediate position, the friction wheel 24 is disengaged from both friction wheels 23—59, whereby the entire machine will be stopped.

One or each of the gear wheels 16 is provided upon the inner face thereof, with a pair of buffers 60, one of which, when the ram 14' is raised or retracted from the mold, will strike the ram, as seen in Fig. 5, in order 30 that the further rotation of the gear wheels 16, will carry the ram with them, to swing the ram to one side away from the mold. When the wheels 16 are rotated in one direction, one of the buffers 60 contacts with the 35 ram, and when said wheels are reversed and rotated in the other direction, the other buffer contacts with the ram. The wheels 16 make practically a complete or almost a complete revolution during each operation, rotating in one direction in one operation, and in the opposite direction in the next. Thus, when the wheels 16 are in starting position with the ram swung to one side, the crank or wrist pin 15' is above the trunnions 17 and when the wheels 16 are rotated 40 in the proper direction, the ram 14' is first returned to depending position and is then forced downwardly into the mold, and after the pin 15' passes its lowermost point, it 45 moves upwardly, thereby retracting the ram from the mold, and when the ram is retracted, the respective buffer 60 engages the ram and moves it toward the opposite side away from the mold.

Means are provided for automatically 50 stopping the machine when the ram is at either of its extreme positions, and for this purpose a rock shaft 61 is journaled in standards 62 carried by the member 3, and has 55 mounted thereon levers 63, one for each gear

wheel 16, and one arm of each lever has a depending cam 64 coöperable with outstanding rollers or studs 65 and 66 carried by the outer side of the respective gear wheel 16. The roller 65 is so arranged, that when the ram is raised and swung away from the mold in one direction, the roller 65 engages the cam 64 and swings the lever 63, which results in the disconnection of the ram from the actuating shaft. The roller 66 is so arranged, that when the ram is raised and swung in the other direction, the roller 66 engages the cam 64, to swing the lever 63 for stopping the machine. The rollers 65 and 66 can be adjusted to different positions, 70 to regulate the operation of the lever 63, the gear wheels 16 being provided with apertures 66^a or other suitable means for the adjustment of said rollers. Pivoted to the other arms of the levers 63 are vertical rods 75 67 which project downwardly and slide through guides 68 carried by those standards 2 to which the bar 38 is attached, and the rods 67 are normally raised by springs 69, to restore the levers 63 to normal position. 80 The push rods 67 when moved downwardly, 85 serve to rotate the shaft 42, to move the yoke 27 downwardly, to disconnect the friction wheel 24 from the friction wheel 23, whereby to stop the machine. For this purpose, a pair of arms 70 are attached to the shaft 42 and project under the rods 67, to be operated thereby, in order that when the rods are moved downwardly, they swing the arms 70 downwardly to an intermediate position, 90 whereby to remove the friction wheel 24 to an intermediate position.

The shaft 42 is also rotated by the table actuating device, to stop the machine with the table either in raised or in lowered position. Thus, a rocking lever 71 is fulcrumed, as at 72, upon the base 1, and a pair of lift rods 73—74 are slidable through guides 75 and 76 attached to those standards 2 to which the bar 38 is attached, and 95 the lower ends of the lift rods 73 seat upon the opposite arms of the lever 71. The upper ends of the lift rods 73—74 project under the arms 70 to raise them under certain conditions, it being noted that the rods 73 and 74 reciprocate in opposite directions. Attached to the lever 71 is a tappet 77 projecting partially across the faces of a disk 80 secured to the end of the shaft 8, in the path of a pair of outstanding pins 78—79 105 carried by said disk. The disk has apertures 81 for the reception of said pins whereby the pins can be adjusted to different positions. The pin 78 is engageable with the tappet 77 when the shaft 8 is rotated to 110 raise the table, whereby to raise the rod 73, and the pin 79 is engageable with the tappet 77 when the table is lowered to normal position, whereby to raise the rod 74.

The machine also includes means for cen- 115

tering the ram when it is returned from one side of the mold to a position above the mold. Such means embodies a pair of arms 90—91 overhanging the ends of the mold 4 past which the head of the ram swings or moves, said arms being provided with up-standing rollers 92 at their free ends to contact with the head and the ram. The arms 90—91 are secured upon the upper ends of 10 vertical shafts or spindles 93 journaled in bearings 94 secured to the corners of the mold at one side thereof, preferably at that side opposite the block removing means. Coiled wire torsional springs 95 are disposed upon the shafts 93 and are arranged 15 to swing the arms 90—91 toward one another over the ends of the mold. The arm 90 has an extension 96 which is connected by a link 97 with the arm 91, whereby both 20 arms 90—91 swing toward and away from the mold simultaneously. When either of said arms is swung away from the mold, the other is also moved away from the mold, and the two arms are moved toward the mold 25 simultaneously. Thus, supposing that the ram 14' is retracted, when it is moved toward one side of the machine, it contacts with one of the rollers 92, and swings the respective arm away from the mold, said 30 roller being forced away from the end of the head of the ram and passing onto the side of said head. The other arm is swung away from the mold at the same time. When the ram returns to position above the mold, it 35 will pass between the arms 90—91, and said arms being spring pressed to move toward the mold, will cause the rollers 92 to clasp the ram therebetween and due to the fact that the movement of the arms 90—91 is 40 limited when they have brought the ram to centered position, they remain at such position during the time that the ram is depressed into the mold. When the ram is again retracted, it passes between the 45 rollers 92.

In operation, supposing that the wheels 16 have rotated clockwise, as seen in Fig. 2, until the ram 14' is retracted and swung to one side, the roller 65 in engaging the cam 50 64 will stop the machine, so that it is in position for a complete cycle of operation. The cam 64 being raised by the roller 65 swings the levers 63 thereby to depress the rods 67 a sufficient amount, to move the arms 55 70 downwardly to intermediate or neutral position, which will rock the shaft 42, to pull the link 52 downwardly. The yoke 27 is thus swung to intermediate position to disengage the friction wheel 24 from the 60 friction wheel 23, thereby stopping the ram. Concrete or other plastic material is first poured in the mold 4, and the operator then depresses the hand lever 48 and swings the same toward the proper side, whereby to 65 throw in the proper clutch of the actuating

shaft 25, and to simultaneously swing the wheel 24 into engagement with the friction wheel 23. The gears 16 are then rotated counter clockwise, as seen in Fig. 2, whereby the ram is depressed. When the wheels 16 70 start to turn, the ram will swing back to pendant position over the mold 4, and as the crank or wrist pin 15' moves to its lowermost position, the ram will be depressed forcibly into the mold, to compress 75 the concrete therein. As the crank or wrist pin 15' continues its movement, it moves upwardly at the right hand side of the trunnion 17, and raises or retracts the ram 14'. As soon as the ram 14' is retracted from the 80 mold, the respective buffer 16 contacts with the ram and the ram is then swung toward the right, as seen in Fig. 2, away from the mold. At the time that the ram is swung away from the mold, the roller 66 engages 85 the cam 64, and swings the levers 63 to depress the rods 67 for stopping the machine, by removing the friction wheel 24 from the friction wheel 23. The machine is thus stopped whenever the ram is retracted and 90 swung out of the way, and it will be noted that whenever the wheels 16 start to turn, to bring the ram to position to enter the mold, the arms 90—91 will serve to properly center the ram above the mold, as above explained. The ram is stopped at the proper time, even though the operator is absent or negligent. When the ram is retracted and moved out of the way toward one side, the operator now raises the lever 28 and swings 100 it sidewise in the proper direction, to throw in the proper clutch whereby the shaft 25 rotates in the proper direction, and to depress the yoke 27 to bring the friction wheel 24 into engagement with the friction wheel 105 59. The friction wheel 59 is rotated by the actuating shaft, and rotates the vertical shaft 55, which in turn rotates the shaft 8, so that the pinions 7 raise the rack bars 6 and table 5. The table thus pushes the 110 block out of the mold 4, and when the table reaches a predetermined position, the pin 78 engages the tappet 77 and swings it, so as to rock the lever 71 and raise the rod 73, whereby said rod raises one of the arms 70 115 to intermediate position, which will raise the link 52 and yoke 27 to disengage the friction wheel 24 from the friction wheel 59, thus stopping the movement of the table actuating device. The completed block can 120 now be removed from the table by first swinging the lever 14 outwardly and upwardly, to turn the shaft 9 and brackets 11 to the position seen in Fig. 11, and then by swinging the lever 14 in a horizontal direction, the brackets 11 will be moved toward one another, so that the arms 13 engage the block, while the arms 12 are brought into place adjacent one side of the block. Then, by swinging the lever 14 downwardly, the 130

brackets 11 are returned to normal position, and the block will now rest upon the arms 12, being transferred from the arms 13 to said arms 12. When the brackets 11 are in normal position, the block can be readily lifted therefrom, or a suitable contrivance for carrying the block can be moved between the arms 12, and then by swinging the lever 14, the brackets 11 can be separated, to transfer the block from the arms 12 onto the block carrying member. The block, however, can be readily lifted from the arms 12 before they are separated. The table 5 is now returned to normal position, by swinging the lever 48 toward the opposite side so as to reverse the connection of the shaft 25 with the pulley wheels 31—32, so that the shaft 25 will rotate in the opposite direction, and the lever 48 is then raised, to lower the yoke 27 in order that the friction wheel 24 will again engage the friction wheel 59. The shaft 8 is again rotated, but in the opposite direction, to move the rack bars 6 downwardly until the table is again in normal position, in which event the pin 79 engages and swings the tappet 77, to raise the rod 74 and its arm 70, which results in the yoke 27 being raised to intermediate position to disconnect the friction wheel 24 from the friction wheel 59, to stop the movement of the table actuating device. This completes the cycle of operation, and the operation is repeated as before, but the wheels 16 are rotated in the opposite direction with the same results.

The present machine is thoroughly efficacious for pressing the concrete within the mold, retracting the ram and moving it out of the way, ejecting the block from the mold, removing the block from over the mold to one side, and returning the table, the machine being stopped automatically when the ram and table reach the ends of their respective movements, whereby the lack of attention of the operator will not result in a continued operation of the machine or the excessive movement of any of its parts. The advantages of this invention will be manifest to those versed in the art, and the other attributes and advantages of the present machine will also suggest themselves without further comment.

Having thus described the invention, what is claimed as new is:

1. In a molding machine, a mold, a ram movable into and out of the mold, and operating means carrying the ram and operable for moving the ram into and out of the mold and for moving the ram alternately to opposite sides away from the mold.

2. In a molding machine, a mold, a ram, means for moving the ram into and out of the mold and to one side away from the mold when retracted therefrom, and means operated when the ram is moved to one side

away from the mold for stopping the movement thereof.

3. In a molding machine, a mold, a rotary member having a wrist pin, a ram connected to the wrist pin to be moved into and out of the mold thereby, and means carried by said member whereby when it is moved in either direction, the ram is swung to one side away from the mold when retracted therefrom.

4. In a molding machine, a mold, a rotary member having a wrist pin, a ram connected to the wrist pin to be moved into and out of the mold thereby, means for oscillating said member in opposite directions, means carried by said member for swinging the ram alternately to opposite sides when the ram is retracted from the mold, and means operable when the ram is swung to either side for stopping the oscillation of said member.

5. In a molding machine, a mold, block ejecting means working therein, a ram movable into and out of the mold, means for moving the ram into and out of the mold and to one side away from the mold when it is retracted therefrom, means for moving the ejecting means in opposite directions, actuating means for actuating the second and third mentioned means, means operable when the ram is moved to one side away from the mold for stopping the movement thereof, and means operable when the ejecting means is moved to either position for stopping the movement thereof.

6. In a molding machine, a mold, block ejecting means working within the mold, a ram, means for moving the ram into and out of the mold and to one side away from the mold when retracted therefrom, means for actuating the block ejecting means when the ram is moved to one side away from the mold, and block removing means operable when a block is ejected from the mold for removing the block.

7. In a molding machine, a mold, a ram coöperating therewith, a table working within the mold, a wheel operatively connected with the ram, a second wheel operatively connected with the table, a lever, an actuating shaft carried by said lever, a third wheel carried by the actuating shaft and alternately engageable with the first and second mentioned wheels, oppositely rotating wheels mounted loosely upon said shaft, clutches for alternately connecting the last mentioned wheels with the actuating shaft, a slidable and rocking shaft, a controlling member connected to the second mentioned shaft, means operatively connecting the second mentioned shaft with said clutches and lever for alternately connecting the last mentioned wheels with the actuating shaft and for swinging said lever to bring the third mentioned wheel into and out of engagement with the first and second mentioned

- 6 wheels, means operated when the ram is at one position for operating the second mentioned shaft to move said lever to an intermediate position away from the first mentioned wheel, and means operated when the table is at one position for operating the second mentioned shaft to move said lever to intermediate position away from the second mentioned wheel.
10. 8. In a molding machine, a mold, a table working therein, actuating means for raising and lowering said table and including a disk, an actuating device adapted to be connected with and disconnected from said means and having means for changing its direction of rotation, a slideable and rocking shaft operatively connected with the actuating device whereby when said shaft is rocked, the actuating device is connected with and disconnected from the table actuating means, and when the shaft is slid, the direction of rotation of the actuating device is changed, arms carried by said shaft, a rocking lever having a tappet, rods operated by said lever and cooperating with said arms for rocking said shaft to disconnect the actuating device from said table actuating means, and pins carried by said disk, one being engageable with said tappet when the table is raised and the other being engageable with the tappet when the table is lowered.
15. 9. In a molding machine, a mold, a rotary member having a wrist pin, a ram pivotally connected with said wrist pin to be advanced into and retracted from the mold when said rotary member is rotated in opposite directions, and means carried by said rotary member engageable with the ram when it is retracted for swinging the ram to one side away from the mold.
20. 10. In a molding machine, a rotating member having a wrist pin, a ram connected to said wrist pin, an actuating device adapted to be connected with and disconnected from said member and having means for changing its direction of rotation, a sliding and rocking shaft connected with said device for changing the direction of rotation thereof when the shaft is slid and for swinging said device into and out of connection with said member when the shaft is rocked, said shaft having an arm, a lever having a cam, a rod operated by said lever and operating with said arm for rocking the shaft when said lever is moved by means of the cam which disconnects the actuating device from said member, and a stud carried by said member engageable with said cam when the ram reaches a certain position.
25. 11. In a molding machine, a table working therein for lifting a block therefrom, and an oscillatory device adapted to be swung to a position to engage the ejected block and to be swung to one side to remove the block from over the mold.
30. 12. In a molding machine, a mold, a table movable therein for ejecting a block therefrom, and an oscillatory device mounted adjacent said mold and including brackets movable to and from one another, said brackets being swingable over the mold to engage the ejected block and being swingable to one side to remove the block from over the mold.
35. 13. In a molding machine, a mold, a table working therein for raising a block therefrom, and an oscillatory device adjacent said mold including brackets movable toward and away from one another, said brackets having outstanding arms and other arms arranged at an angle therewith and spaced farther away from one another, the second mentioned arms being engageable with a block raised by the table when the brackets are swung over the mold and moved toward one another, and the first mentioned arms being adapted to receive and support the block when the brackets are swung outwardly.
40. 14. In a molding machine, a mold, a table movable therein for raising a block therefrom, a rock shaft at one side of the mold, a pair of brackets slideable on said shaft and adapted to be swung over and away from the mold, said brackets being adapted to engage a block raised by the table when the brackets are swung over the mold and movable toward one another, and means for rotating said shaft and moving said brackets toward and away from one another.
45. 15. In a molding machine, a mold, a table movable therein for raising a block therefrom, brackets carried by the mold, a rock shaft journaled within said brackets, brackets slideable upon said shaft and having outstanding arms and other arms arranged at an angle therewith and spaced farther from one another to engage a block raised by said table when the brackets are swung over the mold and moved toward one another, a hand lever fulcrumed to said shaft, and links connecting said lever and second mentioned brackets.
50. 16. In a molding machine, a mold, a rotary member having a wrist pin, a ram pivotally connected with said wrist pin to be advanced into and retracted from said mold, means carried by said rotary member engageable with the ram when it is retracted for swinging the ram to one side away from the mold, operating means connected with said rotary member and having means for making and breaking the connection, and means controlled by said rotary member when the ram is retracted and swung away from the mold to disconnect said member from the actuating means.
55. 17. In a molding machine, a mold, a ram

- cooperable therewith, means for advancing and retracting the ram into and out of the mold and constructed and arranged to move the ram to one side away from the mold
- 5 when it is retracted, actuating means, and means for connecting and disconnecting the aforesaid means and controlled by the first mentioned means to disconnect said means when the ram is retracted and moved to one
- 10 side.
18. In a molding machine, a mold, a ram mounted for movement into and out of the mold and when retracted for movement to one side of the mold, and spring pressed
- 15 means associated with the mold moved out of the way when the ram is moved to one side of the mold and operable to center the ram when it is returned into position to enter the mold.
- 20 19. In a molding machine, a mold, a ram mounted for movement to be projected within and retracted from the mold and when retracted to move to one side from the mold, and a pair of spring pressed arms connected
- 25 with one another and having means for engaging the ram to center it relative to the mold, said arms being adapted to be swung away from the mold by the ram when it is moved to one side.
- 30 20. In a molding machine, a mold, a ram
- projectile into and retractable from the mold and when retracted being movable to one side, a pair of spring pressed devices for centering the ram relative to the mold, either of said devices being adapted to be moved 35 out of the way by the ram when it is moved to one side, and means operatively connecting said devices whereby they operate simultaneously.
21. In a molding machine, a mold, a rotatable member having a wrist pin, a ram pivotally connected with said wrist pin to be advanced into and retracted from the mold, means carried by said rotary member for engaging the ram when it is retracted 40 for swinging the ram to one side away from the mold, and spring pressed means associated with the mold for centering the ram when it is returned into position to enter the mold, said spring pressed means being 45 moved out of the way by the ram when the ram is moved away from the mold.

In testimony that we claim the foregoing as our own, we have hereto affixed our signatures in the presence of two witnesses.

JOHN DUNKIN LODGE.
WILLIAM C. PELL.
